UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPE-BAR BLANK.

No. 858,755.

Specification of Letters Patent.

Patented July 2, 1907.

Application filed November 23, 1900. Serial No. 37,421.

To all whom it may concern:

Be it known that I, FRANCIS H. RICHARDS, a citizen of the United States, residing at Hartford, in the county of Hartford and State of Connecticut, have invented 5 certain new and useful Improvements in Type-Bar Blanks, of which the following is a specification.

This invention relates to type-bars and type-bar blanks and has for an object to furnish a typebar or type-bar blank or stock suitable for the formation thereon of characters to form a type-bar and whose form and construction shall offer especial facilities for removing dirt or foreign matter that may collect on the face of the bar, thereby enabling a number of the bars to be piled up fairly and solidly.

15 A further object sought to be attained by the present invention is a reduction in the total area of contact between bar and bar, that the tendency to an uneven bearing of one on the other shall be diminished, while another object is to furnish such a type-bar construction as shall allow a given amount of typographic matter to be set up with a minimum quantity of metal.

In the drawings accompanying and forming part of this specification, Figure 1 is a view of the side face of a portion of a type-bar blank embodying my present improvement. Fig. 2 is a similar view to Fig. 1 but shows the opposite face. Fig. 3 is a cross section of such a blank. Fig. 4 is a view of the upper edge thereof. Fig. 5 is a view on a somewhat larger scale showing the upper edge of a part of a type-bar with characters formed thereon. Fig. 6 is a perspective view of a number of assembled type-bars, one of the bars being shown as removed from its assembled position in association with the other bars and laid down, the better to exhibit the configuration of and the relation between contiguous faces. Fig. 7 is a view similar to Fig. 1 and shows a modification. Fig. 8 is a view similar to Fig. 2, showing the opposite face of this modified form. Fig. 9 is a cross section of this modified form of blank. Fig. 10 is a top view thereof; and Fig. 11 is a perspective view 40 illustrating the configuration of and the relation existing between contiguous type-bar faces when made according to this modification.

Similar characters of reference designate corresponding parts in all figures.

45 This invention may be said to comprise in general a construction for a blank and a type-bar formed therefrom involving channels or depressions made in either one or both of the faces of the bar in contact with an adjacent bar or bars. In case both sides of the blank 50 and the bar formed therefrom are provided with depressions, those on one side will preferably be made to run in another direction to the direction taken by the depressions on the other face. This relative arrangement will bring the depressions and elevations sepa-

rating them on any one face angularly disposed with 55 respect to the corresponding features on a contact face, and thus the contact between bar and bar will be over a number of small areas where the elevations cross each other.

Fig. 1 is a view of the side face of a type-bar blank 60 B and shows in this instance a series of longitudinal or lengthwise channels or depressions 2 formed therein. Four such channels are shown, but of course, it is readily understood that this particular number in no wise defines the limits of the invention. Reference 65 to Fig. 2 shows the opposite face of the blank B, in which there is also formed another series of channels or depressions 3, which are represented as being angularly disposed with respect to the channels on the face presented by Fig. 1. In the particular arrangement 70 shown, the channels or depressions 3 extend transversely across the bar. I do not, however, wish to be limited to this particular relative disposition of the series of channels to each other and to the blank, nor to the construction illustrated above, since but one 75 face of the blank may be channeled while the other face is formed with a flat, smooth surface, and still come within the spirit of the present invention. And, again, either one or both of the two series of channels may extend at another angle to the boundary line of a 80 face of the bar instead of substantially parallel or perpendicular thereto. These channels may be formed upon the blanks during the process of making, and when one edge of the blank is left in condition to have wrought, or otherwise formed thereon, characters to 85 constitute it a type-bar. An illustration of characters formed or wrought upon the edge of a blank is the bar set forth in the patent to Roswell H. St. John, for type-bar, No. 435,777, dated September 2, 1890. In respect to the particular direction to be given to the 90 channels, whether longitudinal, transverse, or otherwise, this will depend to some extent upon the particular process of blank-forming adopted. If the blanks are wrought to shape, the channels may extend lengthwise or longitudinally on one side, while the other side 95 is channeled or not, as desired.

It has been before stated that preferably the two series of channels or depressions cross each other along any contacting surface. This is shown in Fig. 6, which represents a number of bars assembled or piled together, 100 one of the bars being removed from its assembled position to illustrate the relative disposition of the channels. It will be evident that upon similar faces of the separate bars, considered with respect to the top or bottom of the characters thereon, the channels run in 105 the same direction; hence upon assembling the bars the two series of depressions 2 and 3 will extend across each other and contact between the bars will occur

along portions of the elevations separating the depressions. Dirt and foreign matter is liable to accumulate on the faces of the separated bars, for the removal of which these channels present especial facilities, since the operator in the act of piling up the bars can by a sliding movement of one bar upon another sweep the material into an adjacent channel or depression.

The particular arrangement of the channels or depressions above described results in a configuration of the upper edge of the bar, such as shown in Fig. 4, and on a larger scale in Fig. 5. A more uniform appearance is secured if the series of channels or depressions on each side is extended diagonally or at an oblique angle to the boundary line of the side face and opened out through one or both of the longitudinal edges as shown in Figs. 7 to 11, inclusive, where the depressions thereat upon the two faces are shown opposite to each other. These series of depressions upon the two faces are also shown angularly disposed with respect to each other and this angle, as in the former instance, is represented as substantially a right angle, although the angle may be a different one if thought advisable. In this disposition of the channels also their relative angular arrangement upon contacting surfaces is secured, as pointed out, with respect to the former construction, and which is clearly shown in Fig. 11.

It will be noticed that in these type-bars and type-bar blank constructions the area of contact between bar and bar is much reduced from what it would be if no channels were formed in the faces thereof. This is of advantage, as it diminishes the liability to an uneven bearing of one bar upon another, owing to the

fact that the surfaces of the bars are uneven or not truly plane surfaces. The construction also facilitates the reduction of the face of a bar to a plane. It will also be understood that the presence of these channels or depressions represents a less amount of metal necessary for a bar than if the same was not channeled; hence for a given amount of typographic matter the weight of metal necessary to set it up is considerably less than if the same was set up from unchanneled bars.

Having described my invention, what I claim is—

1. A typebar provided on one of its side faces with comparatively closely spaced channels or depressions, angularly disposed with respect to a boundary line of the side face of the typebar, and with intervening bearing ribs of substantial width, and on the other of its side faces with comparatively closely spaced bearing ribs of substantial width, and intervening channels narrower than the channels on its former side. 45

2. A type-bar provided with channels or depressions upon its opposite faces which run in different directions with respect to each other. 50

3. A type-bar provided with channels or depressions upon its opposite faces, those on one face running transversely to those on the other face. 55

4. A type bar provided with channels or depressions upon its opposite faces, the channels in one face running lengthwise of the type bar and the channels in the other face running transverse thereto. 60

5. A type bar having upon one face spaced apart channels or depressions, and upon the opposite face spaced apart channels or depressions, the channels or depressions upon one side being disposed at an angle to those upon the opposite side. 65

FRANCIS H. RICHARDS.
